ASH TRAY

Albert W. Jefferis, Jr., North Hollywood, Calif.,
assignor to Jerene Jefferis, North Hollywood,
Calif.

Application September 11, 1948, Serial No. 148,552

Term of patent 3½ years

(Cl. D85—2)

To all whom it may concern:

Be it known that I, Albert W. Jefferis, Jr., a citizen of the United States, residing at North Hollywood, in the county of Los Angeles and State of California, have invented a new, original, and ornamental Design for an Ash Tray, of which the following is a specification, reference being had to the accompanying drawing, forming part thereof.

Figure 1 is a side view of an ash tray showing my new design.

Figure 2 is a view similar to Figure 1 and showing the said ash tray turned at an angle of ninety degrees with respect to the showing thereof in Figure 1.

Figure 3 is a top plan view of Figure 1.

I claim:

The ornamental design for an ash tray, as shown.

ALBERT W. JEFFERIS, JR.
